UNITED STATES PATENT OFFICE.

EDWARD BUCKLIN, JR., AND SEDGEWICK A. SUTTON, OF NORTH PROVIDENCE, RHODE ISLAND.

IMPROVED WINDOW-SCREEN.

Specification forming part of Letters Patent No. 58,982, dated October 23, 1866.

To all whom it may concern:

Be it known that we, EDWARD BUCKLIN, Jr., and SEDGEWICK A. SUTTON, of North Providence, in the county of Providence and State of Rhode Island, have invented a new and useful Improvement in Window-Screens; and we do hereby declare that the following specification, taken in connection with the drawings making a part of the same, is a full, clear, and exact description thereof.

Figure 1 is an elevation of a window with our screen covering the lower sash. Fig. 3 is a view of the extension-rail shown in Fig. 1. Figs. 2 and 4 are modifications of the same.

The purpose of our invention is to provide a more efficient means for securing the screen in the window-frame, so that by the sudden force of a draft of wind it shall not be liable to be blown from its place, but at the same time admitting of ready removal when desired.

Screens for windows the frames of which are designed to be held in place by the pressure against the side of the window-easing obtained from a spring have heretofore been employed; but the sudden opening of a door, occasioning an unusual draft of air through the open window, will frequently dislodge them.

In the accompanying drawings, A represents the window-frame, and B the sliding sash. C is a netting, commonly called a "mosquito-bar," which is attached at the top and at the bottom edges to the rails D D'. These rails can be conveniently made in two parts, which parts are connected by the right- and left-screw-coupling E, so as to be capable of extension lengthwise by turning such coupling; or, instead thereof, a single-acting screw-coupling (E, Fig. 2) can be used for the same purpose—that is to say, a coupling with a thread cut upon only one end of it, the other end having no thread, so as to admit of its turning

freely in or around the end of the other portion of the rail, according as the socket is made in the rail or in the end of the coupling; and also a button-head with a spindle, having a thread cut upon such spindle, and fitting a socket with a corresponding thread in one end of the rails E, Fig. 4, could also be employed with the same result, which modifications would be equivalents for the means exhibited in Figs. 1 and 3.

It is evident that the degree of friction required to hold the mosquito-bar in place against the force of a draft of air can be readily obtained by operating such screw in a direction to extend the length of the bar, and that also the mosquito-bar can be removed altogether from the window, or the netting rolled up around either bar, adjusting the screen to the opening of the sash as conveniently as in any other screen of a similar kind.

It will be observed that whether the rails D are increased or diminished in length by the rotation of the screw, the width of the screen C is increased or diminished in exactly the same proportion, so that whatever may be the width of the window to which the rails are adjusted, the screen will always completely fill it, leaving no gaps for the admission of insects.

What we claim as our invention, and desire to secure by Letters Patent, is—

Attaching the screen directly to two supporting-rails, D and D', in such manner that the width of the screen may be increased or diminished in the same proportion as the length of the rails, as and for the purpose described.

EDWARD BUCKLIN, JR.
SEGEWICK A. SUTTON.
